UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

QUAD-BLOCK FOR SLUG-CASTING MACHINES.

1,193,269.

Specification of Letters Patent.

Patented Aug. 1, 1916.

Application filed July 2, 1915. Serial No. 37,665.

To all whom it may concern:

Be it known that I, DAVID S. KENNEDY, a citizen of the United States, residing at Brooklyn, in the county of Kings and State 5 of New York, have invented certain new and useful Improvements in Quad-Blocks for Slug-Casting Machines, of which the following is a specification, reference being had therein to the accompanying drawing.

10 My invention relates to typographical machines, such as linotype machines of the general organization represented in the United States Letters Patent to O. Mergenthaler, No. 436,532, wherein circulating matrices are released from a magazine in the order in which their characters are to appear in print and then assembled in line, the composed line transferred to the face of a slotted mold, the mold filled with molten 15 metal to form a slug or linotype against the matrices which produce the type characters thereon, and the matrices thereafter returned through a distributing mechanism to the magazine from which they started.

20 It frequently becomes desirable to cast slugs with very large printing characters, for use in display work, head lines, etc., and it is not always possible or convenient to employ in the machine individual matrices 25 of ordinary form large enough to carry the special characters required. My present invention, therefore, is intended to provide a composite matrix containing such characters, and to this end, I make use of the 30 well known "quad block," wherein I mount a series of matrix sections to make up the line, the sections being readily removable or interchangeable to permit the composition of any desired matter.

35 In the accompanying drawing, I have shown my invention merely in preferred form and by way of example and as applied to a machine of the class stated, but obviously it is susceptible of various other modifications and adaptations which will still be 40 comprised within its spirit, and it may be applied to type or dies as well as to matrices.

Generally speaking, I desire it to be understood that I do not limit myself to any specific form or embodiment, except in so far as such limitations are specified in the claims.

Referring to the drawing:

45 Figure 1 is a perspective view of my im-

proved quad block. Fig. 2 is a vertical section thereof; Fig. 3 is a section on the line 3-3 of Fig. 2; and Figs. 4 and 5 are perspective views of two detached matrix sections, one having a character impression in 50 its edge, and the other being plain so as to act as a spacer.

55 My improved quad block comprises a body portion A, of the usual form, so as to be supported in a linotype machine in the regular way for coöperation with the mold. In its front face the body portion A is provided with a longitudinal groove or recess A¹ containing a series of letter-character sections X arranged in word groups and other 60 quad sections or spacers Y, interposed between the word groups and also arranged at the outer ends of the groove. When thus assembled, the parts constitute in effect a single composite matrix equal in length to 65 that of the line required. It will be noted that the groove A¹ is of dove-tail shape and that the matrix sections are made to correspond, so that when they are assembled in the groove, they will be held against edge-wise displacement and with their front or operative edges flush with the front face of the body portion, thus presenting a smooth surface which fits tightly against the mold during the casting operation. However, to 70 permit the ready insertion and removal of the matrix sections, the greater portion of the upper wall of the groove A¹ is cut away, it being closed by a plate B pivoted to the body portion A, as at B¹, and held in 75 firm but yielding engagement with the upper ends of the inserted matrix sections by strong leaf springs A² fastened to the body portion A and located within recesses A⁴ in the rear face thereof. By swinging the 80 plate B upwardly to the position shown in Fig. 1, complete access may be had to the matrix sections, which can thus be readily removed or interchanged, either independently or in group. To permit their easy 85 removal, the sections X and Y are formed in their ends with notches X² and Y² to receive some suitable instrument or to afford a gripping surface for the fingers. If desired, the plate B may be provided with a 90 grip portion B² to facilitate its movement.

95 When the sections X are assembled in the matrix body, it is necessary that their characters be inverted, or stand with their tops pointing downward, this being their proper 100

110

and customary position. In order to insure this result, the sections X are provided in their edges with notches X¹ adapted to fit over a longitudinal bar or ledge A³ fixed to the body portion A and projecting into the groove A¹, the location of the notches X¹ being such that the ledge may enter them only when the matrix sections are inserted in the groove in the proper position, that is, with their characters inverted. The same necessity, however, does not exist in case of the spacers Y, which can be set in the groove with either end up, they being provided in their rear edges with notches Y¹ of such extent as to fit over the ledge A³ in either position. In this connection it will also be noted that the spacers Y are formed in both ends with the notches Y² to permit their ready removal when either end is uppermost.

20 I have herein shown and described my invention merely in preferred form and by way of example, and it will be apparent that many changes and variations will suggest themselves to those skilled in the art without departure from its scope. Thus, the details concerned in the support of the matrix sections, or in their independent removal, or in their proper location in the matrix body, as well as the form of the matrix sections, or the particular characters contained therein, etc., may be variously modified, within the province of the skilled mechanic.

Having thus described my invention, its construction and mode of operation, what I claim and desire to secure by Letters Patent of the United States is as follows:

1. A quad-block for slug casting machines comprising a body portion formed with laterally projecting ears to adapt it for support in such machines, and a series of interchangeable matrix sections supported therein side by side, the whole constituting an assembled matrix line for use in said machine.
2. A quad-block for slug casting machines comprising a body portion formed with laterally projecting ears to adapt it for support in such machines, and a series of independently removable matrix sections supported therein side by side, the whole constituting an assembled matrix line for use in said machine.
3. A quad-block for slug casting machines comprising a body portion formed with laterally projecting ears to adapt it for support in such machines, and a series of matrix sections supported therein side by side, some of the sections containing letter-characters and arranged in word groups, and others being plain and interposed between the word groups to act as spacers, the whole thus constituting an assembled matrix line for use in said machine.
4. A quad-block for slug casting machines comprising a body portion formed with lat-

erally projecting ears to adapt it for support in such machines formed in its front face with a longitudinal groove or recess and a series of matrix sections supported in said groove with their forward edges flush with the front face of the body portion, the whole constituting an assembled matrix line for use in said machine.

5. A quad-block for slug casting machines comprising a body portion formed in its front face with a longitudinal groove open at one side, a series of matrix sections supported in the groove and a locking plate secured to the body portion to close the groove at its open side and hold the matrix sections therein against removal, the said plate being movable at will from its operative position to permit the removal of said sections.

6. A quad-block for slug casting machines comprising a body portion, and a series of matrix sections supported therein, the said body portion being provided with a movable locking plate to engage the matrix sections and hold them against removal.

7. A quad-block for slug casting machines comprising a body portion formed with a longitudinal groove, and a series of matrix sections supported in the groove, the said body portion being provided with a spring-pressed pivoted locking plate to engage the matrix sections and hold them against removal from the groove.

8. A quad-block for slug casting machines comprising a body portion, a series of matrix sections adapted to be supported thereby, and means to prevent the support of a matrix section in an improper position in the body portion.

9. A quad-block for slug casting machines comprising a body portion having a recess, a series of matrix sections adapted to be inserted in said recess, and means constituted by the relative formation of said parts to prevent the insertion of a matrix section in said recess in an improper position.

10. A quad-block for slug casting machines comprising a body portion and a matrix section adapted to be inserted therein, one of said parts being formed with a notch and the other with a ledge to enter the notch, and the said notch and ledge being so related as to prevent the insertion of the matrix section in an improper position in the body portion.

11. A quad-block for slug casting machines comprising a body portion and a series of character bearing sections adapted to be inserted therein and formed with notches in their rear edges, the said body portion being provided with a longitudinal bar to engage in said notches and so related thereto as to prevent the insertion of the sections in the body portion in an improper position.

12. A quad-block for slug casting ma-

DISCLAIMER.

1,193,269.—*David S. Kennedy, Brooklyn, N. Y. QUAD-BLOCK FOR SLUG-CASTING MACHINES.* Patent dated August 1, 1916. Disclaimer filed April 17, 1919, by the patentee, the assignee, *Mergenthaler Linotype Company*, consenting.

“Enters disclaimer as follows:

“First: In respect to each of claims 5, 6, 7 and 9 of said patent, I hereby disclaim any combination of the recited elements except when and unless the body portion of the quad block is formed so as to be supported in a linotype machine in the regular way for coöperation with the mold employed in said machine.

“Second: In respect to claim 8 of said patent, I hereby disclaim any combination of the recited elements except when and unless the means to prevent the support of a matrix section in an improper position in the body portion of the quad block are distinct from or independent of the means or parts whereby the matrix sections are supported in said body portion.

“Third: In respect to each of claims 10 and 11 of said patent, I hereby disclaim any combination of the recited elements except when and unless the body portion of the quad block and the matrix section or sections are relatively constructed so that the latter may be supported in the former independently and without the aid of the ledge or longitudinal bar when engaged in the coöperating notches.”
